(57) **CLAIM**

We claim the ornamental design for a glove, as shown and described.

DESCRIPTION

The file of this patent document contains at least one drawing executed in color. Copies of this patent document with color drawings will be provided by the United States patent and Trademark Office upon request and payment of the necessary fee.

FIG. 1 is a top perspective view of a right hand glove according to a first embodiment, showing our new design;

FIG. 2 is a top view thereof;

FIG. 3 is a left side view thereof;

FIG. 4 is a right side view thereof;

FIG. 5 is a top perspective view of a left hand glove according to a second embodiment, showing our new design;

FIG. 6 is a top view thereof;

FIG. 7 is a right side view thereof;

FIG. 8 is a left side view thereof;

FIG. 9 is a top perspective view of a right hand glove according to a third embodiment, showing our new design;

FIG. 10 is a top view thereof;

FIG. 11 is a top perspective view of a left hand glove according to a fourth embodiment, showing our new design; and,

FIG. 12 is a top view thereof.

Any line in a black-lined drawing or colored drawing may provide a boundary line of a claimed design element. A boundary line of a claimed design element may be defined in an area between lines in a black-lined drawing or a colored drawing. An element or a subset of any combination of elements in a drawing may form a claimed design. Any portion of the glove shown in broken lines is included for the purpose of illustrating environment and forms no part of the claimed design.
